CALENDAR

Filed Sept. 11, 1925

Fig. 1

Fig. 3

Fig. 4

Fig. 2

A circular calendar wheel with twelve segments, each containing a month name: JAN, FEB, MAR, APR, MAY, JUN, JULY, AUG, SEP, OCT, NOV, and DEC. The segments are arranged in a circle, with JAN at the bottom and DEC at the top. The entire wheel is enclosed in a circle with a dashed line.

UNITED STATES PATENT OFFICE.

THOMAS M. EAGAN, OF DETROIT, MICHIGAN.

CALENDAR.

Application filed September 11, 1925. Serial No. 55,707.

My invention relates to improvements in a calendar designed for use in association with a fountain pen or pencil or some such similar article, and is intended to be made a part of the barrel or cap of the pen or pencil and to be visible through the end thereof.

An object is to provide a simple, inexpensive calendar construction so designed as to be received within the end of a fountain pen barrel or cap. The calendar is capable of being easily read and it is accurate and positive in operation. It comprises a minimum number of movable parts so compactly arranged as to fit within the limited space provided.

An important improvement consists in the provision of a plurality of concentrically disposed independently rotatable disks arranged within the end of the barrel or casing of the pen or pencil and visible through apertures therethrough, each of which disks bears calendar data and is independently revolvable to bring such data in position to be used.

A meritorious feature lies in the employment of a plurality of superimposed disks to indicate the days of the month. One of these disks carries the digits, the other disk carries figures adapted to be read in combination with the digits of the co-operating disk, said disks being independently rotatable for the purpose set forth.

The above objects and advantages together with others of importance will more fully appear from the following description, appended claims and accompanying drawing, in which:

Figure 1 is an elevation of a fountain pen provided with my improvement.

Fig. 2 is a cross-sectional fragmentary view through a pen barrel fitted with my improvement and taken on the line 2—2, Fig. 3.

Fig. 3 is an end elevation of the barrel of a fountain pen fitted with my improvement.

Fig. 4 is an elevation of one of the disks.

Fig. 5 is an elevation of a disk which co-operates with the disk shown in Fig. 4.

Fig. 6 is an elevation of an intermediate disk.

Fig. 7 is an elevation of the axially positioned disk.

My calendar construction is of such a character as to be fitted within the limited

space provided in the end of the barrel or cap of the fountain pen. It is likewise suitable for use in connection with a pencil or other similar article. For convenience of manufacture I have shown it as assembled within a screw cap 10, which may be threaded as at 12 to the end of a pen barrel 14. This cap is here shown as provided with a plurality of radially spaced apertures 16, 18 and 20.

I provide a plurality of disks each bearing calendar data. These disks are concentrically arranged within the cap with intervening washers or bearings 22. The central disk 24 carries the days of the week arranged thereabout to be brought successively into position to be viewed as the disk is rotated. The disk may be rotated with the point of a pencil or other similar instrument. The intermediate disk 26 bears the names of the months arranged thereabout to be brought into position to be successively viewed through the aperture 18 as the disk is rotated.

The outer disk which is visible through the aperture 20 comprises two independent sections or disks 27 and 28 spaced from each other by a washer 30 so as to be independently rotatable. The disk 28 carries the digits arranged thereabout in spaced relationship and adapted to be viewed through the aperture 20 and through apertures 32, 32, in the disk 28 to indicate the days of the month up to 9. This disk 28 may be independently rotated when either aperture 32 of the disk 27 is in registration with the aperture 20 of the casing to bring the digits on disk 28 successively in position to be viewed through said apertures.

The disk 27 carries the figures 1, 2 and 3 each alongside an aperture 34 whereby one of said figures may be read through the aperture 20 in combination with a digit on the disk 28 visible through the aperture 34. The digits are so arranged about the disk 28 that it is rotatable in a clockwise direction to bring them successively into position for proper viewing and the figures 1, 2 and 3 each alongside an aperture 34 are so arranged about the disk 26 that such disk is rotatable in a counterclockwise direction to bring the figures into proper position to be viewed to indicate the days of the month. The disks are held in place by a plate 36 and each disk is so mounted in position as to be freely independently rotatable but

adapted to hold any position to which it may be rotated.

The calendar as above set forth serves as a perpetual calendar; it is a convenient accessory to a fountain pen in that it is always possible to quickly learn the day of the week or month as the calendar is a permanent part of the pen; it does not serve to make the pen or pencil any more bulky than would ordinarily be the case, and it is instantly accessible and conveniently operable for the purpose set forth.

What I claim is:

1. A unit comprising a cylindrical cap 15 apertured in its end wall, a disk in the cap engaging the end wall and having a portion visible through the end wall, and a pair of ring-shaped superposed disks surrounding the first disk, the outer one of the pair engaging the end wall of the cap and having angularly-spaced apertures, portions of the outer one of the pair being visible through the end wall of the cap and portions of the inner one being visible through the end wall 25 of the cap and through said apertures, the superposed disks being substantially equal in thickness to the first disk.

2. In an article of the class described, a cylindrical cap apertured in its end wall, a

disk within the cap engaging said end wall 30 and visible therethrough, a ring-shaped disk surrounding the first disk and also engaging the end wall and visible therethrough, a pair of superimposed ring-shaped disks surrounding the second disk and engaging the end wall and also visible therethrough, the outer one of said superimposed ring-shaped disks provided with a plurality of angularly arranged apertures through which the inner one of said superimposed 40 disks is visible.

3. In an article of the class described, a cylindrical cap having an apertured end wall and a plurality of concentrically arranged disks disposed within said cap in 45 substantially the same plane and adjacent the apertured end wall of the cap to be viewed therethrough, a plate holding said disks against the end wall of said cap, one of said disks comprising two superimposed 50 sections of which the one adjacent to the end wall is provided with a plurality of angularly arranged apertures through which the second one is visible.

In testimony whereof, I sign this specification.

THOMAS M. EAGAN.
